US00D957575S

(12) **United States Design Patent** (10) **Patent No.:** **US D957,575 S**
Downey et al. (45) **Date of Patent:** **** Jul. 12, 2022**

(54) **FAUCET**

(71) Applicant: **Spectrum Brands, Inc.**, Middleton, WI (US)

(72) Inventors: **David Downey**, Mission Viejo, CA (US); **Tony Zhang**, Xiamen (CN)

(73) Assignee: **Spectrum Brands, Inc.**, Middleton, WI (US)

(**) Term: **15 Years**

(21) Appl. No.: **29/744,473**

(22) Filed: **Jul. 29, 2020**

(51) **LOC (13) Cl. 23-01**

(52) **U.S. Cl.**

USPC **D23/238**

(58) **Field of Classification Search**

USPC D23/238, 239, 240, 241, 242, 243, 246, D23/247, 248, 249, 250, 251, 252, 253, D23/254, 255, 256, 257

CPC . E03C 1/01; E03C 1/0409; E03C 1/04; E03C 1/0401; E03C 1/025; E03C 1/0408; E03C 1/0402; E03C 1/0405; E03C 1/0412; Y10T 137/5339; Y10T 137/6014; Y10T 137/6021

Primary Examiner — Samantha Wood

(74) *Attorney, Agent, or Firm* — Banner & Witcoff, Ltd.

(57) **CLAIM**

The ornamental design for a faucet, as shown and described.

DESCRIPTION

FIG. 1 is a front perspective view of a faucet showing our new design;

FIG. 2 is a left side view thereof;

FIG. 3 is a right side view thereof;

FIG. 4 is a front view thereof;

FIG. 5 is a rear view thereof;

FIG. 6 is a top view thereof;

FIG. 7 is a bottom view thereof;

FIG. 8 is a front perspective view of a second embodiment of a faucet showing our new design;

FIG. 9 is a left side view thereof;

FIG. 10 is a right side view thereof;

FIG. 11 is a front view thereof;

FIG. 12 is a rear view thereof;

FIG. 13 is a top view thereof; and,

FIG. 14 is a bottom view thereof.

The broken lines immediately adjacent to the photographic area define the bounds of the claimed design and form no part thereof. The unshaded areas within the broken lines form no part of the claimed design.

1 Claim, 14 Drawing Sheets
